UNITED STATES PATENT OFFICE.

CHARLES H. DISHMAN, OF HENDERSON, KENTUCKY.

EXCAVATING-SCRAPER.

1,023,303.

Specification of Letters Patent. Patented Apr. 16, 1912.

Application filed August 9, 1910. Serial No. 576,330.

To all whom it may concern:

Be it known that I, CHARLES H. DISHMAN, a citizen of the United States, residing at Henderson, county of Henderson, and State 5 of Kentucky, have invented certain new and useful Improvements in Excavating-Scrapers, of which the following is a specification.

This invention relates to excavating 10 scrapers.

The present invention relates to those excavating scrapers employing a derrick suspended bucket or scoop, such as are particularly used in railroad work, and it has for 15 its object the provision of a scraper constructed and operated in a novel manner which may be readily manipulated by a new arrangement of cables, so that it can be hoisted or lowered, moved from the 20 excavation pit to the spoil, and readily dumped.

The object of the invention is accomplished by the provision of certain novel attachments on the excavating scoop or 25 bucket, combined with cables operated from the winding drums in a manner which will be fully set forth hereinafter.

In the accompanying drawings:—Figure 1 is a side elevation showing the invention 30 in use on an approved form of steam derrick; Fig. 2, an enlarged side elevation of the scoop or bucket reversed from the position shown in Fig. 1; Fig. 3, a plan view thereof; and Fig. 4, a vertical section on the 35 line 4—4 of Fig. 2.

Referring first to Fig. 1, the winding drums 1 and 2 are those of any approved form used on the steam derrick shown, the latter having the usual jib 3.

40 My invention relates solely to the excavating scraper or bucket 4 and its attachments, together with the cables 5 and 6 which wind on the drums 1 and 2, respectively.

45 The scoop or excavating bucket 4 is provided with the usual open top and is open at one end and it has the usual knife or points 7. Carried by opposite sides of the scoop or bucket 4 are upright plates 8, each 50 of which has a sheave 9 and idlers 10 and

11. Pivoted at 12 to opposite sides of the excavating scoop or bucket are the arms 13 which are adapted to swing to a more or less horizontal and to a more or less vertical position. These arms are connected 55 to the cable 6 so that they move in unison, and they are also connected to the cable 5 by the branches 14 and 15 which pass around idlers 16 disposed near the bottom of the excavator scoop, and thence between 60 the sheaves 9 and idlers 11 and finally they run against the idlers 10. On the sides of the scoop or bucket 4 are abutment plates 17, against which the arms 13 strike when they are in their lowered and more or less 65 vertical position.

In the operation of the excavator the derrick and the jib are manipulated in the usual manner. When the knife 7 is taking into 70 the excavation pit, the drum 2 is in action and the cable 6 is drawn taut, being in the position shown in Fig. 1, the drum 1 being slightly let out to compensate for the travel of the scoop or shovel. When the scoop or shovel is loaded, both of the drums 1 and 75 2 draw upon the cables 5 and 6 and make them taut, but the swinging arms 13 are then against the abutments 17, giving a truss-like effect in connection with tension on both cables and when the scraper is 80 swung from the pit to the spoil bank, it will be kept horizontal, the suspending cable 5 carrying the greater part of the load and the tension on both the cables causing the knife or cutting edge to be held up so that 85 the dirt cannot fall out. When it is desired to dump the scoop, the cable 6 is paid out and the scoop then turns to an upright position on account of the release of the tension of the cable 6 on the swinging arms 13. 90

Having thus described my invention, what I claim as new and desire to secure by Letters Patent, is:—

In an excavating scraper, the combination with an excavating scoop, of swinging arms 95 carried on one end part thereof, a sheave on the scoop, a suspending cable which runs over said sheave and thence angularly to its suspending stretch and is connected to the arms aforesaid and adapted to pull them 100

in one direction, and a free pulling cable directly connected to the arms and adapted to pull them in the opposite direction, said arms being adapted for movement only by 5 the combined paying out of one cable and the tension of the other cable to effect suspending or tilting of the scoop.

In testimony whereof, I hereunto affix my signature in presence of two witnesses.

CHARLES H. DISHMAN.
